212,207

SPRING CLIP FOR BOOT BUCKLES OR SIMILAR ARTICLES

Domenic A. Zinni, Warwick, R.I., assignor to B. B. Greenberg Co., Cranston, R.I., a corporation of Rhode Island

Filed Nov. 27, 1967, Ser. No. 9,557

Term of patent 14 years

(Cl. D2—422)

FIG. 1

FIG. 2

FIG. 3

FIG. 4

FIG. 5

FIG. 6

FIG. 1 is a rear elevational view of a spring clip for boot buckles or similar articles having my new design, the clip being shown in closed position;

FIG. 2 is an end elevational view thereof;

FIG. 3 is a front elevational view thereof;

FIG. 4 is a top plan view thereof;

FIG. 5 is a bottom plan view thereof; and

FIG. 6 is a perspective view thereof showing the clip in open position.

I claim:

The ornamental design for a spring clip for boot buckles or similar articles, substantially as shown and described.
